CLAIM

The ornamental design of a wearable apparatus for intuition based cognitive assistant, as shown and described.

DESCRIPTION

FIG. 1 is a front view of an embodiment of a wearable apparatus for intuition based cognitive assistant according to our new design;

FIG. 2 is a back view of an embodiment of a wearable apparatus for intuition based cognitive assistant according to our new design;

FIG. 3 is a right elevational view of an embodiment of a wearable apparatus for intuition based cognitive assistant according to our new design;

FIG. 4 is a right view of an embodiment of a wearable apparatus for intuition based cognitive assistant according to our new design;

FIG. 5 is a top plan view of an embodiment in a closed state of a wearable apparatus for intuition based cognitive assistant according to our new design; and,

FIG. 6 is a top plan view of an embodiment in an expandable open state of a wearable apparatus for intuition based cognitive assistant according to our new design.

The present design invention refers to an ornamental design of an article of a wearable apparatus for intuition based cognitive assistant.

The broken lines depict environment only and form no part of the claimed design.
